FLIER FOR SPINNING MACHINES

Harvey E. Herr, Buffalo, N. Y., assignor to Herr Manufacturing Company, Inc., Buffalo, N. Y., a corporation of New York

Application January 24, 1939, Serial No. 252,692

2 Claims. (Cl. 57—116)

This invention relates generally to improvements in the fliers employed in connection with spinning machines.

It has for its object to provide a flier of this character which is so designed as to assure a fixed distance of the outer or overhanging eye-containing portion of the flier wire from its point of attachment to the flier-base, whereby to eliminate the bend of the wire beyond the breaking 10 stress during the spinning operation.

Another object of the invention is to mount the flier wires in a predetermined definite relation on the flier base so as to positively eliminate breakage of the wires during the spinning operation and thereby effect a material saving in time 15 and expense caused from such break-downs.

In the accompanying drawing:

Figure 1 is a fragmentary front view of a portion of a spinning machine showing the improved flier applied thereto. Figure 2 is an enlarged top plan view of the flier and associated bobbin. Figure 3 is an enlarged vertical longitudinal section taken on line 3—3, Figure 2.

Similar characters of reference indicate corresponding parts throughout the several views.

Referring now to the drawing, 10 indicates the revolving spindle of a spinning machine, 11 the bobbin mounted thereon and having a recess 12 in its top containing an inverted cup-like member 13 having an opening 14 therein.

The flier shown in the drawing, by way of example, is of the eccentric type and consists of an attaching sleeve or barrel 15 adapted to be fitted over the bobbin-spindle and terminating at its lower end in an eccentrically-shaped flange 16 adapted to be passed through the cup opening 14 during the application and removal of the flier to and from the spindle. Rotatably mounted on this sleeve is a bearing member 17 to which a base plate or spider 18 is connected 40 and on which the flier wires 19, 20 are detachably mounted. The base plate is provided about the bearing member with an annular groove 21 in which is disposed a rotatable locking ring 22.

Stamped from the base plate at opposite sides of its axis are substantially radially-extending wire-retaining loops 23 which are adapted to receive the shanks of the flier wires. At its diametrically opposite sides the locking ring has vertically-offset webs or flanges 24 which serve 45 to bend the inner ends 25 of the flier wires laterally in the locked position thereof shown in

Figure 2, the vertical webs serving to deflect or spring such ends of the wires laterally to hold and firmly anchor them in the retaining loops 23.

As shown in Figure 2, the wire-retaining loops extend substantially the full length of the spider-arms and terminate approximately at or just short of the outer edges of such arms, thereby providing for a maximum retention of the flier-wires therein. For a given-sized flier, these wires are made of a certain length and the 10 length of the retaining loops vary with the length of the flier wires in a definite predetermined relation or proportion so that the overhanging ends of the wires, that is, the unretained ends thereof extending from the outer 15 ends of the loops 23 which are subject to bending or tension strains during the spinning operation, are of the same length. This definite relationship is predetermined from the breaking 20 stress of the wire used and the length of the overhanging ends of the flier wires is such that the breaking stress is never reached during the spinning operation of the flier, thereby eliminating 25 breakage of the wires when running and the attending time and expense of the subsequent 25 operations required in remedying such a breakdown.

I claim as my invention:

1. A flier for spinning machines, comprising a bearing member, a wire base including oppositely-disposed arms applied to said bearing member and having retaining loops extending substantially the full length of such arms, and flier wires having their inner ends anchored in said loops, those ends of the flier wires extending beyond the base being of a constant length predetermined from the breaking stress of such wires, whereby such wires are not subject to breakage when tensioned during the spinning operation.

2. A flier for spinning machines, comprising a bearing member, and a wire base applied to said bearing member and having substantially radially-disposed retaining loops thereon for receiving the inner portions of the flier wires, said loops varying in length with the length of such wires in predetermined relation so as to leave the unretained, flexing portions of the wires of a constant length, such length being predetermined in relation to the breaking stress of the 50 wires.

HARVEY E. HERR.
